UNITED STATES PATENT OFFICE.

HENRY A. FRACKELTON, OF SCHENECTADY, NEW YORK.

GAUGE COCK.

Application filed April 26, 1921. Serial No. 464,553.

To all whom it may concern:

Be it known that I, HENRY A. FRACKELTON, of Schenectady, in the county of Schenectady and State of New York, have invented a certain new and useful Improvement in Gauge Cocks, of which improvement the following is a specification.

My invention relates to gauge cocks for steam boilers, of the class or type in which the renewal or repair of the seat of the valve members which controls the discharge of fluid from the gauge cock may be effected while the boiler is under steam. The object of my invention is to provide a gauge cock of such type in which renewal or repair of the valve seat may be made, whenever required, more expeditiously and with less manipulation of parts than has heretofore been found practicable.

20 The improvement claimed is hereinafter fully set forth.

In the accompanying drawing: Figure 1 is a longitudinal central section through a gauge cock embodying my invention; and, 25 Figs. 2 and 3, transverse sections through the same, on the lines *a a* and *b b*, respectively, of Fig. 1.

In the practice of my invention, referring descriptively to the specific embodiment 30 thereof which is herein exemplified, I provide a tubular body, 1, which is externally threaded at and adjoining one of its ends; for connection to a boiler sheet, and has a collar, 1^a, at its opposite end, forming an 35 abutment for a coupling nut, 2, by which it is connected to a tubular bonnet, 3. An annular valve seat, 4, of metal or suitable composition, is fitted on the top of the body, 1, and is clamped between said body and the bonnet, 3, when the body and bonnet are 40 connected by the coupling nut, 2, which is internally threaded, to engage an external thread on the bonnet. A nipple, 2^a, for the discharge of fluid from the gauge cock, is 45 connected to the wall of the bonnet.

A main valve stem, 5, passes through a packing nut, 6, which closes the upper end of the bonnet, and extends through the latter into the body. A hand wheel, 5^a, is fixed 50 on the upper end of the valve stem and squared faces, 5^b, are formed upon said stem at, and for some distance above, its lower end. The valve stem is of less diameter than the opening in the valve seat, 4, which

difference in diameter, together with the reduction of transverse section effected by the formation of the squared faces on the stem provides sufficient space around the stem for the passage of fluid to the discharge nipple. A screw thread, 5^c, which is ordinarily, and preferably, of left hand lead, is cut on the valve stem, said thread engaging a corresponding internal thread on the bonnet.

A supplemental valve stem, 7, is fitted in the body, 1, said stem having a screw thread, 7^a, of similar lead to that of the main valve stem, cut upon it, which thread engages a corresponding internal thread in the body. The upper end of the stem, 7, is faced off to form an operating closure valve, 7^b, which is adapted to make contact with the valve seat, 4, and a repair closure valve, 7^c, adapted to make contact with a valve seat, 1^b, in the body, is formed on the lower end of the stem, 7. A socket, 7^d, of corresponding transverse section to the squared end portion of the valve stem, 5, is formed at the upper end of the valve stem, 7, and the squared end portion engages said socket, thereby forming a detachable clutch connection of the two valve stems. Channels, 7^e, are milled in the threaded portion of the stem, 7, to permit the free passage of fluid through the body, from the boiler connection to the valve seat, 4.

In the operation of a gauge cock of the construction above described, the operating closure valve, 7^b, being normally seated, and the repair closure valve, 7^c, unseated, when it is desired to deliver fluid from the gauge cock, the valve stem, 7, is turned to the left a sufficient distance to unseat the valve, 7^b, without seating the valve, 7^c. When, for purposes of renewal or repair, it becomes necessary to temporarily close communication with the boiler, the stem, 5, is turned sufficiently further to the left to seat the valve, 7^c. The coupling nut, 2, is then backed off the bonnet, 3, and the bonnet and stem, 5, removed from the body, thereby leaving the valve seat, 4, fully accessible for renewal or repair, upon the completion of which the parts may be quickly replaced in operative position.

The expedition with which renewal or repair of the valve seat may, as above described, be effected, and the small extent of manipulation of parts required therein, will

be obvious to those familiar with the operation of locomotive and other steam boilers.

I claim as my invention and desire to secure by Letters Patent:

- 5 1. The combination, in a gauge cock, of a tubular body; a tubular bonnet; an interposed valve seat; a coupling nut, detachably connecting the body and bonnet; a main valve stem, having a threaded connection with the bonnet; a supplemental valve stem, having a threaded connection with the body; an operating closure valve and a repair closure valve, carried by said supplemental valve stem; and means for detachably connecting the main and supplemental valve stems.
- 10 2. The combination, in a gauge cock, of a tubular body; a tubular bonnet; an interposed valve seat; a coupling nut, detachably connecting the body and bonnet; a main valve stem, having a screw threaded connection with the bonnet; a supplemental valve stem, having a threaded connection
- 15

with the body; an operating closure valve and a repair closure valve carried by said supplemental valve stem; and a clutch connection, by which the main valve stem is engaged with the supplemental valve stem.

3. The combination, in a gauge cock, of a tubular body; a tubular bonnet; an interposed valve seat; a coupling nut, detachably connecting the body and bonnet; a main valve stem, having a threaded connection with the bonnet and a squared end portion; a supplemental valve stem, having a threaded connection with the body and a socket engaging the end portion of the main valve stem; an operating closure valve on said supplemental valve stem, adapted to make contact with the valve seat; and a repair closure valve on said stem adapted to make contact with a seat on the body.

HENRY A. FRACKELTON.
